UNITED STATES PATENT OFFICE.

EDWARD CLARK, OF NEW YORK, N. Y.

KING-BOLT PLATE.

SPECIFICATION forming part of Letters Patent No. 548,957, dated October 29, 1895.

Application filed October 10, 1894. Serial No. 525,493. (No model.)

To all whom it may concern:

Be it known that I, EDWARD CLARK, of New York city, in the county and State of New York, have invented certain new and 5 useful Improvements in King-Bolt Plates, of which the following is a full, clear, and exact description.

The invention relates to the running-gear of vehicles; and its object is to provide new 10 and improved king-bolt plates more especially designed for heavy trucks, wagons, &c., and arranged to reduce the friction to a minimum and to permit of conveniently removing the contacting parts and replacing the same when 15 worn out.

The invention consists principally of a bottom plate formed with a central hub and in its top surface with an annular groove semicircular in cross-section and a bolster-receiving 20 plate formed with a central aperture for receiving the said hub and provided at its under side with an annular bead fitted into the said recess.

The invention also consists of certain parts 25 and details and combinations of the same, as will be fully described hereinafter, and then pointed out in the claims.

Reference is to be had to the accompanying drawings, forming a part of this specification, 30 in which similar letters of reference indicate corresponding parts in all the figures.

Figure 1 is a side elevation of the improvement as applied. Fig. 2 is a plan view of the improvement. Fig. 3 is an enlarged sectional 35 side elevation of part of the same on the line 3 3 of Fig. 2, and Fig. 4 is a perspective view of one of the bearing-bands.

The king-bolt plates A and B are fastened by bolts in the usual manner to the bolster 40 C and the axle-bar D, respectively, as illustrated in Fig. 1. The bottom plate B is formed with a vertically-disposed hub B', through which passes the king-bolt E, as indicated in dotted lines in Fig. 1, and concentric with the 45 said hub B' is an annular groove B², made semicircular in cross-section and formed in the top of the plate B, as illustrated in the drawings. Into this annular recess B² extends and fits the annular bead A', formed 50 on the under side of the plate A and likewise

semicircular in cross-section. The annular bead A' encircles the central aperture, into which projects the hub B', the latter being flush at its upper end with the top surface of the plate A. On the under side of the plate 55 A and concentric to the bead A' is formed a raised ring-shaped wearing-surface A⁴ in contact with a correspondingly-raised surface B⁴, formed on the top of the plate B.

In the wall of the opening of the plate A 60 is formed a recess A², into which fits a bearing-band F, adapted to contact with a corresponding bearing-band G, held in a recess formed exteriorly on the upper end of the hub B', as is plainly shown in Fig. 3. The bearing-bands F and G are preferably made of 65 steel and are split, as indicated in Figs. 2 and 4, the ends of the band F abutting against a projection A³, extending from the plate A into the recess A², and the ends of the band G likewise abut against opposite sides of a projection B³, formed on the hub B' and extending into the recess B².

Now by reference to Fig. 2 it will be seen that the projections A³ and B³ are disposed in 75 different places, so that the ends of the bands do not come over each other when the vehicle is turning around a curve.

It will be seen that by the arrangement described the bearing-bands F and G can be 80 conveniently removed from their recesses and replaced by new ones when worn out, and the said bands are prevented from turning in their recesses on account of abutting on the projections A³ and B³. It will further be seen 85 that by fitting the annular bead A' into a correspondingly-shaped groove B² in the plate B, I reduce the friction between the plates to a minimum, at the same time relieving the king-bolt E and the bolts for fastening the 90 plates in position of all strain. As the bead, owing to its peculiar cross-section, presents no sharp corners in contact with the wearing-surface on the plate B, the truck is free to turn readily around curves or street-corners, 95 especially when heavily loaded, without strain on the other parts of the running-gear. It is understood that the plates A and B may be transposed—that is, the plate B can be fastened to the bolster C and the plate A to the 100

axle-bar D—without deviating from my invention.

Having thus fully described my invention, I claim as new and desire to secure by Letters 5 Patent—

1. A bolster plate formed with a central aperture having a recess in its wall, and a bearing band fitted in the said recess, substantially as shown and described.

10 2. A bolster plate formed with a central aperture having a recess in its wall, and a split bearing band fitted in the said recess, and abutting with its ends on opposite sides of a

projection extending into the recess, substantially as shown and described.

3. A bottom plate formed with a central king bolt hub having an exterior recess, and a split bearing band, fitted into the said recess and abutting with its ends on opposite sides of a projection formed on the hub and 20 extending into the said recess, substantially as shown and described.

EDWARD CLARK.
